UNITED STATES PATENT OFFICE.

CHARLES HOWARD SMITH, OF SHORT HILLS, NEW JERSEY, ASSIGNOR TO INTERNATIONAL COAL PRODUCTS CORPORATION, OF RICHMOND, VIRGINIA, A CORPORATION OF VIRGINIA.

CARBONIZING FURNACE RETORT.

1,409,598.

Specification of Letters Patent. Patented Mar. 14, 1922.

Application filed March 26, 1920. Serial No. 368,854.

To all whom it may concern:

Be it known that I, CHARLES HOWARD SMITH, a citizen of the United States, and a resident of Short Hills, county of Essex and 5 State of New Jersey, have invented certain new and useful Improvements in Carbonizing Furnace Retorts, of which the following is a specification.

The invention relates to a furnace having 10 a retort or retorts for performing a carbonizing operation, and an object of the invention is to construct the furnace so that the heat condition in each retort is under easy control, due to the construction and arrangement of the heating flues located at each side of the retort.

In the preferred form of the invention a recuperator is employed to preheat the air that supports combustion. Also in such preferred form the masonry providing the pre-heated construction is of fire-clay brick while the masonry providing each retort and the heating flues is principally of silica brick and arrangements are made to provide expansion spaces to permit or take care of the greater expansion of the silica brick as compared with the fire-clay brick when the furnace is heated.

In the preferred form suitable bracing 30 and buckstay construction is provided and an arrangement is made whereby a part of the bracing is yieldable in respect to certain relatively fixed girders or buck-stays. This yielding bracing, frequently referred to 35 herein as a floating frame work or floating retaining member, is however supported in such a manner that it is constantly spring-pressed toward the masonry that the bracing is intended to maintain in place. Further, 40 there is provided suitable anti-friction means, to wit, several sets of rollers that permit a vertical upward movement of the brick work in the furnace relative to said yielding bracing as the furnace is being heated; or a vertical downward movement of the 45 same brick work as the furnace cools.

The invention particularly relates to a furnace having the features of construction above referred to and also other features, all 50 of which are herein clearly described and set forth.

The furnace which is the basis of the present invention is particularly applicable to the carbonizing of briquets made from coal

or from coal residue and which coal or coal residue has admixed therewith binding material, as pitch, and which binding material insures or renders possible the making of firm, coherent briquet structures, when raw briquets made from said mixture are 60 carbonized at sufficiently high temperatures and for a sufficient length of time.

In my Patent No. 1,276,429 granted August 20th, 1918, entitled Briquets and method of making the same, there is described a 65 manner in which strong, coherent, free-burning, smokeless briquets can be produced by partially carbonizing a high volatile coal, by adding to the partially carbonized coal or resulting residue a proper mixture of binding material, such as pitch, by forming the resulting mixture into briquets, and by subsequently carbonizing the raw briquets thus formed.

In my Patent No. 1,334,180 granted March 16th, 1920, entitled Method of manufacturing briquets, there is described the manner in which coals of non-caking type can be formed into strong, coherent, free-burning, smokeless briquets by first mixing with the 80 non-caking coal, when in finely divided form, an admixture containing caking coal and binding material, such as pitch, by forming the resulting mixture into raw briquets, and by carbonizing the raw briquets thus formed 85 at sufficiently high temperatures and for a sufficient length of time.

The furnace which is the subject of the present invention is particularly adaptable for the commercial performing of the briquet carbonizing operation employed in carrying out the invention described in the patents above referred to. The carbonizing of the briquets is carried out in what may be referred to as an oven, but what is in fact an 90 enclosed carbonizing retort, or retorts, from which the vapors and gaseous products that are given off during the carbonizing are conducted to any suitable storage means and made available for future use. The carbonizing furnace which is the basis of the present invention may be properly referred to as a furnace-retort, but it is more frequently referred to as an inclined carbonizing furnace since the floors of the ovens or retorts that 105 provide the carbonizing compartments or carbonizing spaces slope downwardly from the charging end of the furnace toward the

discharging end thereof. The carbonizing compartments or spaces in each set are vertically arranged forming a tier and the carbonizing spaces of each tier constitute what 5 may be referred to as a carbonizing chamber. The construction which defines the carbonizing compartments or spaces is such that the member or part which provides the floor of one carbonizing compartment or space 10 becomes or provides the roof of the carbonizing compartment or space immediately below it. On each side of each tier of vertically arranged carbonizing compartments there is located a series of vertically extending combustion flues or heating flues having suitable means whereby the heat conditions can be 15 readily controlled within each combustion flue.

The furnace is also provided, as previously indicated, with a recuperator which 20 may be described as a means for heating, by the hot waste gases or products of combustion leaving the furnace, the incoming air that is employed or required to support 25 combustion that takes place in the combustion chamber. The recuperator which, as previously indicated, is made of fire-clay brick is constructed so as to provide alternately arranged series of air ducts, conduits 30 or passageways and waste gas ducts, conduits or passageways. With such a construction there is a ready interchange of heat from the hot waste gases through the masonry walls that define the ducts, conduits or passageways of the recuperator to 35 the cold incoming air.

As illustrating a specific embodiment of the inclined carbonizing furnace wherein the invention can be and is realized reference is made to the accompanying drawings, 40 forming a part of this specification, in which drawings,

Figure 1 is a vertical longitudinal sectional view of the inclined carbonizing furnace. In this view the carbonizing portion has a retort provided with a carbonizing chamber subdivided by shelves or partitions into vertically arranged carbonizing compartments or spaces. In this view there is 45 also seen the arrangement of the ducts, conduits or passageways whereby the hot waste gases from the several heating flues or combustion flues—that are located on each side of the retort or carbonizing chamber—follow a sinuous path through the recuperator portion of the furnace. Figure 1 is a sectional view taken as on the plane indicated by the line 1—1 of Figures 5, 7, 8, 9, 10 and 11 looking in the direction of the arrows.

60 Some of the iron work constituting the bracing or frame work for holding or maintaining the masonry of the furnace in place is also shown in Figure 1, as well as certain portions of the piping for handling the gases or vapors that are driven off; also the iron

work of the charging and discharging doors and the poke-hole closures hereinafter referred to. In Figures 2 to 14 inclusive only the masonry structure of the inclined carbonizing furnace is illustrated, with the exception that the position of certain of the iron frame work is indicated in Figures 5 and 6.

Figure 2 is a vertical longitudinal sectional view of the same furnace shown in Figure 1. In Figure 2 the section is taken through the heating or combustion flues. The view also shows the arrangement of the ducts, conduits or passageways of the recuperator through which the incoming air 70 passes in a sinuous path on its way to the combustion flues. This view is taken on the plane indicated by the line 2—2 of Figures 6, 8, 9, 10 and 11 looking in the direction of the arrows.

Figure 3 is a vertical view taken as along the broken line 3—a—b—c—d—e—f—g—h—m—m—o—3 of Figures 10, 11, 12 and 13 looking in the direction of the arrows.

Figure 4 is a vertical sectional view showing a main air duct or passageway into the lower end of which the heated air is received from a header passageway leading from the recuperator, and from the upper inclined portion of which there branches 90 horizontally and transversely extending passageways or laterals for conducting the air to or adjacent to the upper ends of the combustion or heating flues. Figure 4 is a view taken as on the plane indicated by the line 4—4 of Figures 7, 9, 10 and 11 looking in the direction of the arrows.

Figures 5 and 6 are vertical end views of the masonry work as seen looking toward the discharge end of the furnace and the charging end thereof, respectively. In each of these figures there are also indicated by dot and dash lines some of the members of the iron work and buck-stay and bracing construction.

Figure 7 is a vertical transverse sectional view taken as on the vertical and transversely extending plane indicated by the line 7—7 of Figure 1. In this view there is shown the heating flue arrangement with 115 respect to the retorts or carbonizing compartments thereof. In said view there is also shown the damper control arrangement at the lower end of each flue; there is also shown the manner in which the air comes 120 from the air passageways of the recuperator into transversely extending header openings or passageways leading to the upwardly extending main air duct or passageway. This is a view taken as on the plane also indicated by the line 7—7 of Figures 2, 4, 10 and 13 looking in the direction of the arrows.

Figure 8 is a vertical sectional view taken as on the plane indicated by the line 8—8 of Figures 1 and 2 looking in the direction 130

of the arrows. This view clearly shows how the silica brick construction of the carbonizing portion rests upon or is supported by the fire-clay brick construction of the recuperator.

Figure 9 is a vertical transverse sectional view of the upper portion of the furnace structure and is a view taken as on the plane indicated by the broken line 9—9 of Figure 10 1 looking in the direction of the arrows. In Figure 9 there is clearly seen the manner in which air passes from the main air duct through the transversely extending passageways or laterals, thence through damper 15 controlled openings into the upper ends of the combustion flues shown therein. The damper arrangement at the lower end of each of the combustion flues shown in this figure is somewhat different from the damper 20 arrangement of the combustion flues shown at the lower end of the combustion flues in Figures 7 and 8. In Figure 9 there is also illustrated the manner in which the waste products of combustion pass into the transversely extending header opening or 25 passageway at the charging end of the furnace and from thence into the waste gas passageways leading to or from the recuperator. This figure is also a sectional view 30 taken as on the plane indicated on the line 9—9 of Figures 2, 4, 10 and 14.

Figure 10 is a horizontal sectional view taken as on the plane indicated by the broken line—a step line—10—10 of Figs. 1 and 2 35 looking in the direction of the arrows, and in this figure there is clearly illustrated the arrangement of the passageways leading from the lower ends of the several combustion flues to the main waste gas flues. In 40 this view there is also illustrated the damper arrangement for determining the size of these passageways.

Figure 11 is a sectional view, one-half taken as on the plane indicated by the broken 45 line 11—11 and the other half taken as on the plane 11a—11 of Figure 1 looking in the direction of the arrows. In other words, in this figure there is illustrated at one end the charging opening leading to the carbonizing compartment. At one side of the other end there is indicated a discharge opening leading from the carbonizing compartment, while at the other side of the same end there are indicated certain poke-holes or 55 openings through which rods are inserted to facilitate the discharge of the contents of the furnace.

Figure 12 is a sectional view taken as on the plane indicated by the broken line 12—12 60 of Figures 1 and 2 looking in the direction of the arrows. This view clearly shows the manner in which the heated air from the recuperator passes into the transversely extending header openings or passageways at 65 one end—at the discharge end—of the fur-

nace. It also shows the arrangement of the air passageways and the waste gas passageways relative to each other.

Figure 13 is a sectional view taken as on the plane indicated by the line 13—13 of Figures 2 and 4 looking in the direction of the arrows. This view shows certain features of the recuperator construction and also the location of the openings through which certain tie rods pass that are employed in holding the buck-stays in the metal frame work construction.

Figure 14 is a sectional view one-half of which is taken on the broken line 14—14 of Figure 2 and the other half of which is taken on the broken line 14a—14a of Figure 2 looking in the direction of the arrows. This view illustrates the expansion spaces with which the furnace construction is provided. The long narrow transversely extending white spaces of this figure, when taken in conjunction with Figure 2, illustrate the expansion spaces provided between the fire-clay brick of the recuperator and the silica brick of the carbonizing portion of the furnaces.

Figure 15 is an end view partially broken away of the metal work construction with which the furnace is provided at the discharge end thereof.

Figures 16 and 16a constitute an end view partially broken away of the metal work construction with which the furnace is provided at the charging end thereof.

Figure 17 is a vertical longitudinal view 100 of the metal frame work or buck-stay construction with which the furnace is provided at one side thereof.

Figures 18 to 22 inclusive are details relating to the manner in which the floating frame work construction with which the bracing or buck-stay construction is provided is yieldably supported and carried by vertically extending main girders or buck-stays.

Figures 23 to 25 inclusive illustrate the 110 construction of the door at the discharge end of each retort.

Figures 26 and 27 illustrate the details of construction of the door and the chute employed at the charging end of each retort; and 115

Figures 28 and 29 illustrate the details of the structure for closing the poke-holes.

Reference will now be made to the drawings in detail.

Masonry construction.

The inclined carbonizing furnace construction comprises a vertically and transversely extending main end wall 1 at the charging end of the furnace, a vertically and transversely extending main wall 2 at the discharging end thereof, a vertically and longitudinally extending main wall 3 at one side of the furnace—the right hand side—and a vertically and longitudinally

extending main wall 4 at the other side of the furnace—the left hand side.

The main end walls and the main side walls are preferably of fire-clay brick ma-

sonry construction. In the furnace illustrated there is also shown at the right and left hand side thereof masonry walls 5 and 6 of any suitable brick, as ordinary red brick, if a single furnace construction is employed.

10 Either or both of these walls might be of fire-clay brick if it were a wall of an adjacent furnace of a battery of inclined carbonizing furnaces. In any event, however, the walls 3 and 5 on the one hand might 15 be collectively referred to as a main side wall or the wall 3 could be referred to as a main side wall. In like manner the walls 4 and 6 might be collectively referred to as a main side wall or the wall 4 alone could be referred

20 to as a main side wall. The inclined furnace is provided with an inclined roof 7 extending horizontally from side wall to side wall. This roof 7 is declined from the charging end wall to the discharging end wall and extends the full space between these walls. The furnace also has an intermediate portion or main floor member 8 extending from side wall to side wall and downwardly from the wall 1 at the charging end of the

30 furnace to the wall 2 at the discharging end thereof. Below this main intermediate floor member 8 there is provided the recuperator portion 9 of the inclined carbonizing furnace. This recuperator portion 9 is of ma-

35 sonry construction formed of fire-clay brick and upon this recuperator there is supported the intermediate portion or main floor member 8 and the structure carried thereby. Said intermediate floor member 8 is of

40 silica brick, as is also that portion of the structure which defines in the main the carbonizing compartment and the heating flues at each side thereof. In order to enable a proper supporting of this silica brick construction the upper or top portion 10 of the recuperator is of fire-clay brick arranged in step formation. The under side of the silica brick intermediate portion or floor member 8 is arranged in inverted step formation

50 and the horizontals of the intermediate member rest upon the horizontals of the step formation of the roof of the recuperator, as is readily apparent from an inspection of Figures 1, 2 and 3. The silica brick, however,

55 has a greater coefficient of expansion than the fire-clay brick and hence in the building of the furnace there are left gradually increasing expansion spaces between the ver-

60 ticals of the respective step and inverted step formations in passing from the discharge end of the furnace toward the charging end thereof. These expansion spaces are designated as 11 in the figures just referred to and also in Figure 14.

65 In order that the construction of the sup-

porting means for the upper structure or carbonizing portion of the furnace will be at this time more readily understood, the recuperation portion 9 will first be described. The figures which particularly relate to the recuperator construction are 1, 2, 3, 7, 8, 9, 12, 13 and 14, the arrangement of the waste gas ducts X of the recuperator being shown in Figure 1; the arrangement of the incoming air ducts Y of the recuperator in Figure 2; portions of some of the waste gas ducts X and portions of some of the incoming air ducts Y being shown in Figure 3; the alternate arrangement of the waste gas ducts X and air ducts Y being shown in the lower portion of the transverse view Figures 7 and 8, the latter—Figure 8—also showing the manner in which the silica brick construction of the carbonizing portion rests upon the fire-clay brick construction of the recuperator. The manner in which the waste gases pass into the header opening Z at the charging end of the furnace and from thence into the waste gas ducts X of the recuperator is shown in Figure 9. The manner in which the heated air passes from the upper inclined air ducts Y into the header openings W at the discharge end of the furnace is shown in Figure 1 and the manner in which the waste gases flow through ducts X and run in counter direction to the air passing through ducts Y is shown in Figures 12 and 13. In Figure 13 there is shown in section the partitions 12 that define the lower walls of the inclined air passageway whereby the heated air from the charging end of the furnace is conducted to the header openings or passageway W at the charging end of the furnace (see also Figure 2). In Figure 13 there are also shown openings 13 in each side wall through which tie-rods 14 extend for holding the uprights or girders of the metal frame work in place. For the tie-rods and their positions see Figures 1, 5, 6, 15, 16^a and 17. For further views of these openings see also Figures 3, 4, 5 and 6. The expansion spaces 11 provided between the silica brick masonry and the fire-clay brick masonry when the furnace is first constructed, in order to take care of the differential expansion in a longitudinal direction which exists between the fire-clay brick and the silica brick, are shown in plan in Figure 14, as previously indicated. In Figure 14 there are also shown expansion spaces 15 for permitting and taking care of expansion in a transverse direction.

From the figures just referred to in connection with the recuperator construction, and particularly figures such as 7, 8 and 12, 125 it will be seen that the air and gas ducts are defined in part and are separated by vertically and longitudinally extending intermediate walls 16 through which the heat passes from the outgoing products of com-

bustion or waste gases to the incoming air. The sinuous passageways or ducts are provided by horizontal partitions, such as partition 17 between waste gas ducts X and partition 18 between incoming air ducts Y.

From what has preceded it will be noted that the recuperator is of relatively strong construction formed of fire-clay brick and amply strong to support the carbonizing portion 10 of the furnace resting upon it. The carbonizing portion of the furnace and particularly the walls through which the heat is transferred for effecting the carbonizing is made of silica brick. From an inspection 15 of the vertical sectional views of this portion of the furnace it will be seen there are vertically and longitudinally extending partitions 19. These partitions 19 extend from the inclined intermediate portion or main 20 floor member 8 to the roof 7 and from end wall to end wall, and a carbonizing chamber 20 is located between what may be referred to as a set of these partitions 19. In other words, the partitions 19 may be considered 25 as arranged in sets and between the walls of each set of walls there is located a carbonizing compartment. At each side of each carbonizing compartment there are located vertically and transversely extending 30 partitions 21 which, with the partitions 19, provide or define along each side of each carbonizing chamber a series of combustion flues or heating flues 22. The carbonizing chambers 20 are clearly seen in Figure 1 35 while the heating or combustion flues 22 are readily seen in Figure 2, and the arrangement of the carbonizing chamber relative to the heating flues is seen in Figure 3 when taken in connection with such figures as 7, 40 8 and 9. The vertically and transversely extending partitions 21 at the extreme right and left hand sides of the furnace structure run into the extreme right and left hand vertically and longitudinally extending partitions 45 19. Said partitions 21 may be considered as extending from the main side walls 3 and 4 respectively to the vertically and transversely extending partitions 19 adjacent thereto, while the partitions 19 adjacent 50 cent to the side walls 3 and 4 may each be considered as a lining for the main side wall; or, as silica brick work for completing or lining that portion of the flue structure adjacent to the main side walls.

55 It will therefore be seen that the silica brick structure extends not only from end wall to end wall but from main side wall 3 to main side wall 4, which main side walls are of fire-clay brick.

60 Figures 2 and 12 show the manner in which the header openings or passageways W at the discharge end of the furnace receive the heated air from the recuperator. Figure 4 shows a main air duct or passageway 23—there being one in each side wall

of the furnace—that receives the heated air from the header opening or passageway W and that conducts the air to the inclined portion 24 of the duct or passageway 23 and which portion 24 is located in the upper or 70 roof portion of the furnace. From said inclined portion 24 of each main air duct there extend transversely extending laterals or branches 25 that are built in the roof portion of the furnace as, for example, illustrated in 75 Figure 8 or Figure 9. From these transversely extending laterals or branches 25 the heated air passes through openings 26, regulated as to size by dampers 27, into the upper ends of the combustion flues, as is clearly 80 seen from Figures 8, 9 and also from Figures 2 and 3. Gas is also supplied through tubular refractory members 28 inserted in one corner of the opening at the upper end of each combustion or heating flue. Each flue 85 is covered as by any suitable member, such as 29, which can be removed in order to permit of the insertion of a rod or bar that may be utilized to adjust or position the damper members at the lower end of the flue. This 90 member 29 also normally covers the opening through which the corresponding damper 27 is accessible and whereby the latter can be positioned. Each flue has at the lower end thereof two sets of dampers the upper set of 95 which is designated as 30 and may be referred to as the damper for effecting temporary control, while the lower damper designated as 31 may be considered as a relatively permanent damper which when once 100 positioned determines the size of the relatively fixed opening leading from the lower end of the combustion flue into a main waste gas duct X corresponding thereto. The construction of the dampers just described is 105 readily seen from an inspection of Figures 1 to 7 of the drawings. The damper construction in all of the flues is substantially the same, there being a slight deviation in the construction employed in the flues nearest 110 the charging end. The flues nearest the charging end are shown in Figure 9 and in this figure the damper 32 corresponds as to its function to the damper 31 shown in Figure 7. Access to the damper 32 is obtained by removing a brick member 32^a shown in Figure 3. The products of combustion from the combustion flues or heating flues 22 flow past the damper 30, thence laterally past damper 31 into a main waste gas 115 duct X¹ corresponding thereto. A main waste gas duct X¹ is provided below each carbonizing chamber and is built in the silica brick work masonry providing the carbonizing portion of the chamber. The main 120 waste gas duct X¹ just referred to is an inclined duct through which the gases pass upwardly to the main header or passageway Z at the charging end of the furnace, as is readily seen in Figures 1, 2 and 3. The 130

products of combustion from the flues nearest the charging end flow past dampers 32 directly into the header opening Z as is readily apparent from Figures 2, 3 and 9. From the header opening Z the products of combustion pass downwardly through openings 33 (see Figures 1, 9 and 14) into and through the passageways X of the recuperator.

From the description preceding it will be manifest that there is a damper controlled opening for regulating the flow of air into the combustion flues and a damper controlled set of passageways for regulating the flow of the products of combustion from each of the combustion flues. It will also be seen from an inspection of figures, such as 2 and 3 when taken in conjunction with Figure 1, that the combustion or heating flues are arranged along the full length of each carbonizing chamber on the exterior thereof so that all parts of the carbonizing chamber receive heat through the silica walls serving to separate the combustion flues from the carbonizing compartment. The inclined main waste gas flues X¹ being located directly under the carbonizing compartments permit the heat of the hot waste products of combustion to be imparted through the silica inclined wall and the thin floor member directly thereupon to the contents of the carbonizing compartment corresponding. Each carbonizing compartment has shelves or partitions 34, 35, 36 and a relatively thin floor portion 37 of fire-clay brick and capable of withstanding the abrading action of the load carried thereby. The shelves or partitions subdivide the carbonizing compartment 20 into carbonizing chambers or spaces 38.

It will be observed that the middle or centrally located shelf or partition 35 extends to the end wall at the charging end of the furnace, thus necessitating the lower charging doors and chutes 39 and the upper charging doors or chutes 40. The upper and lower shelves 34 and 36 terminate short of the end wall at the charging end of the furnace. The partitions or shelves 34, 35 and 36 each terminate short of the end wall at the discharging end of the furnace and this permits the employment of a single discharge door 41 which normally closes the lowermost portion of the corresponding carbonizing compartment.

From an inspection of Figure 1, it will be readily apparent that the residue of all material discharged into the furnace, through either of the charging chutes 39 and 40, is readily discharged through the discharge door opening 41. There are times when the charge within some of the spaces or chambers 38 tends to hang or stick therein and in order to facilitate the dislodgment of the charge poke-openings 42 are provided. These are normally closed by the members 65 designated as a whole by 43. The construc-

tion of the charging chute and door for closing the same, of the discharge door, and of the closures for the poke-openings or holes will subsequently be referred to more in detail.

70

Gas pipe construction.

Gases driven off during the carbonizing operation pass through piping 44, into fitting 45. This fitting 45 has therein a movable valve member 45^a which cooperates with seat portions 45^b and 45^c of said fitting. When the valve 45^a is in the upper position shown in dotted lines Figure 1 then the waste gases pass to the hydraulic main 46, from which they are conducted to suitable gas collecting and cleaning apparatus. At the beginning of the carbonizing the gases driven off from the charge are diluted by the air that entered and remained in the carbonizing chamber as the result of a discharge of the contents of the chamber and a subsequent recharge of the same. It will thus be observed that the gases leaving the retort or carbonizing chamber at the beginning of the charge are lean or diluted. As it is not practical to put these lean or diluted gases into the gas holders the movable valve member 45^a is moved to the dot and dash position shown in Figure 1 where access to the hydraulic main is closed. When in this position the passageway through the valve seat 45^b is opened and the gases flowing from pipe 44 through the fitting 45 pass through the opening provided in the valve seat 45^b 100 to a pipe 45^d that opens to the atmosphere or leads to a stack, as the case may be. The carbonizing furnaces are preferably constructed so that they increase in breadth in passing from the charging toward the discharging end thereof, thus lessening the tendency for the charge to arch and clog in the carbonizing compartments. In other words, the dimension *a* at the charging end of the furnace is less than the dimension *b* at the discharging end of the furnace (see Figure 14).

130

Metal frame-work or buck-stay construction.

The metal frame-work for the bracing or buck-stay construction that is relied upon for maintaining or retaining the side walls and end walls of the furnace in place is illustrated in Figures 15 to 22 inclusive, but in this connection reference should also be made to Figures 1, 5 and 6. The buck-stays for retaining the side walls in place are designated as 47 (see Figure 17) and each consists of a pair of rolled flanged members 48 suitably connected by tie plates, as 49. The upper ends of these buck-stays at one side wall are connected to the upper ends of buck-stays at another side wall by suitable tie rods 50. The lower ends of the buck-stays 47 are secured in any suitable manner, as in the

foundation. The buck-stays at the discharge end of the furnace are designated as 51 and their arrangement is clearly indicated in Figure 5. The construction of each buck-stay is shown more in detail in Figure 15 wherein it will be seen that each buck-stay comprises a pair of rolled-channel I-beams 52, 52 connected by transverse members 53 serving to tie the I-beams 52 together. The upper and lower ends of the pair of I-beams 52, 52 are also connected by tie-plates 54. The buck-stays at the charging end of the furnace are designated by 55 and their arrangement is clearly indicated in Figure 6. The details of construction of these buck-stays 55 are clearly indicated in Figures 16, 16^a, Figure 16 showing the upper ends of the buck-stays and Figure 16^a the lower ends. Each buck-stay 55 includes a pair of rolled I-beams 56 connected by transverse members 57. They are also connected by transverse tie plates 58. The buck-stays at the charging end of the furnace and discharging end are connected by suitable tie rods 25 extending from one buck-stay to the other. At the charging end of the furnace there are horizontally and transversely extending I-beams 59 fixedly secured to the lower portion of the buck-stays 55. In other words, these I-beams 59 serve as relatively fixed bars for retaining the end wall of the recuperator portion in place. At both the charging end and the discharging end of the furnace—principally opposite the carbonizing portion of the furnace—there is provided what has been and is herein referred to as a frame work construction. The frame work at the charging end of the furnace and at the discharging end thereof is designated as a whole as 60 and comprises horizontally and transversely extending I-beams or bars 61, 61^a rigidly connected by vertically extending I-beams or bars 62. This frame work construction 60 may be referred to as a floating frame work or floating or yielding retaining member because it is supported in such a manner that it can move or yield in a horizontal direction as the carbonizing portion of the furnace expands. The manner in which this floating frame work is maintained in place will subsequently be described more in detail.

The vertically extending I-beams 62 of this frame work may be considered as vertically extending track members which constantly press against anti-friction rollers 63 that in turn press against track members 64 which are in the form of flat ribbed plates resting on and pressed by the rollers against the masonry construction. Below each roller 63 there is secured on each vertically extending I-beam or track member 62 an angle-iron or bracket member 62^a that is relied upon to assure the rollers 63 being in check 65 until they are moved upwardly as the result

of the furnace construction expanding when being heated. This detail of construction is brought out in Figures 23 and 24 that are drawn to a larger scale than the same parts appear in Figures 15, 16 and 16^a.

70

The flat track plates 64 providing means for holding the castings of the discharge door construction, of the poke-hole door construction and of the discharge door construction in place.

75

At the discharge end of the furnace there are secured to the track members 64 the main castings 65 of the poke-hole closure structure and also the main castings 66 of the frame work for the discharge door closure structure. At the charging end of the furnace there are secured to the flat track plates or members 64 main castings 67 of the charging chute or door construction. It will thus be seen that the track members or plates 64 not only serve to exert pressure against the masonry construction of the carbonizing portion of the furnace but also serve to maintain in proper position the main metal parts used in association with said masonry construction of the carbonizing portion of the furnace.

80

85

90

Mechanism whereby the floating frame work construction 60 is yieldably supported 95 from the vertically extending buck-stays 51 or 55.

95

Referring now to the means whereby the floating frame work construction is maintained in place, reference will be made, in addition to Figures 15, 16 and 16^a, to the details shown in Figures 18 to 22 inclusive. Therein it will be observed that there is provided at each end of each horizontally and transversely extending I-beam or bar 61 or 61^a a suitable spring construction which is employed to force the floating frame work toward the masonry construction of the furnace. This spring construction is designated as a whole by 68 and comprises two sets of concentric springs the inner one of which springs is designated by 69 and the outer one by 70. The outer ends of the springs in each set of springs engage or are engaged by an adjustable cap member 71 carried by a bracket construction 72 which is in turn secured to and carried by the vertically extending upright or channel I-beam 52 or 56 of the girder or buck-stay construction 51 or 55, as the case may be. The inner ends of the springs in each set of springs press against a cup-shaped cap member 73 carried by and secured to the end of the horizontally and transversely extending I-beam 61 or 61^a as the case may be. The bracket construction 72 includes a bracket plate 74 which is secured to one of the upright I-beams 52 or 56 as the case may be by means of angle-irons 75 which are secured as by riveting or bolt-

100

105

110

115

120

125

130

ing to the plate 74 on the one hand and the web 76 of the I-beam on the other. These bracket plates 74 are arranged in sets, as will be readily manifest from an inspection 5 of Figure 18. For each set of the bracket plates at one side of the girders or buck-stays there is provided a corresponding set at the opposite side. This arrangement of brackets with suitable springs pressing 10 against them can be relied upon to provide outwardly extending thrust whereby the pressure, at one side of the girders can be equalized by pressure on the other side and in this manner prevent or oppose a tendency 15 for the girders to be twisted or warped about their vertical axes. As the brackets on one side of the buck-stays are the same as those on the opposite side a description of one bracket construction applies to both. The 20 bracket construction at the top or right hand side of Figures 18 and 19 is shown in section, while that at the bottom or left hand side of Figure 18 does not appear in section. From the portion of Figure 18 just referred to in 25 conjunction with Figure 19, it will be observed there are provided filler pieces 77 and angle-irons 78. Each of these angle-irons has a flange 79, one end of which flange is secured by rivets 80 to flanges of two angle-irons 75. In Figure 18 it will also be seen 30 that there are angle-irons 81 having flanges 82 and 83. The flanges 82, the filler pieces 77 and the flanges 79 of the angle-irons 78 are all connected to the bracket plates 74 by any 35 suitable means, as bolts 84. Upright members 85 having threaded openings 86 may be referred to as nut members and these are held in place as by bolts 87 serving to connect them to the flanges 83 previously referred to. By the construction just described 40 the nut members are rigidly secured to the bracket plates 74. Each of the angle-irons 78 has an outer flange designated as 88 that has an end portion 89 which abuts the 45 flanged portion 90 of the upright I-beam 52 corresponding thereto and by this construction there is opposed any tendency for the bracket plates 74 to bend either up or down; in fact the construction just described is such 50 that it readily resists forces in vertical directions. Adjusting screws 91 pass through the threaded openings 86 of the nut members and the inner ends of these screws press against the adjustable cap members 71. By this 55 means the pressure in an inward direction against the upper ends of the springs is readily under control. At each end of the transversely extending I-beams or bars 61 or 61^a there are secured angle-irons 92 having 60 flanges 93 and 94 which are the members secured as by bolts 95 to the web portion of the I-beams. The cup-shaped members 73 are secured to the flanges 94 of the angle-irons 92 by any suitable means, as bolts 96.

65 An inspection of the upper portion (right

hand side) of Figure 18 shows that there is only a small amount of clearance, indicated as by 97, between bracket plates 74 on the one hand and the members, to wit, members 73, secured to the horizontally and transversely extending I-beams or bars 61, on the other. The result of this construction is that the metal frame work 60 is practically restricted as to vertical movement but due to the spring construction it can be pressed outwardly by the masonry of the furnace as the latter expands. In the lower left hand side of Figure 19 there is indicated a construction wherein the cup-shaped members of the spring construction instead of being 70 secured to transversely extending I-beams or bars are secured to any suitable member, as 75 98—for connecting them. This connecting member is pressed by the springs against the opposite wall. The spring construction at 80 each side of the vertically extending I-beams of the buck-stay construction is relied upon to impart an outward thrust to the corresponding bracket construction. Because of the spring and bracket construction being 85 90 on both or opposite sides of each set of vertically extending I-beams or buck-stays the tendency for the buck-stays to become twisted is lessened or opposed. Instead of utilizing the bracket construction at one side 95 of the buck-stays merely as a resisting member to oppose the thrust of the floating frame work construction the same bracket construction can be relied upon to maintain in place the ends or beams of a 100 second floating frame work construction similar in its function to the floating frame work construction which is maintained in place by the brackets in the manner described.

105

Charging door construction, discharge door construction and poke-hole closure construction.

The charging door and chute of the furnace, designated as 39 is shown in Figures 26 and 27. The chute comprises a tubular body member 99 having flanged portions 100 secured to the track members or rolled plates 64 at the charging end of the furnace. The tubular body member 99 comprises inward extensions 101 entering openings—constructed to receive them—that are provided in the brick work that is behind the track members 64. A door 102 normally 110 seals the charging opening and this door is pivotally connected at 103 to a lever 104. One end of this lever is fulcrumed on an eccentric pin 105 carried by a bracket 106 on the tubular body member 99. The outer or 115 free end of the lever is normally held in place by a pivoted yoke 107 which when in the position shown in Figure 26 holds the free end of the lever in place. When this 120 pivoted yoke 107 is in place a handle 108 on 125

130

the eccentric pin 105 can be thrown to the position shown and this forcibly presses the door 102 against its seat. The swinging of the handle 108 away from the door releases the pressure of the door against its seat and this permits a swinging of the pivoted yoke 107 from over the lever; in this way the door is readily opened. The discharge door construction is shown in Figures 23 to 25. The frame work casting 66 of the discharge door construction has flanges 109 bolted to track members 64 at the discharge end of the furnace and the casting 66 also has an inwardly extending portion 110 which enters an opening provided to receive it on the masonry that is behind the track members 64. A door 111 closes the discharge opening and is pivotally mounted at 112 on a lever 113 which lever is in turn pivoted at 114 to a lug on the casting 66. At the lower end of the lever 113 there is provided a catch 115 and this catch is pivotally connected to the lever 113 by an eccentric pin 116 operated by a handle 117. When the catch is in place, as shown in Figure 24, the handle 117 can be thrown in a manner whereby the cam on the pin forces the door firmly against its seat and whereby when it is desired to open the door the handle can be turned in a reverse direction so as to permit a release of the catch and a subsequent opening of the door. The contents within the carbonizing furnace and near the discharge door are subjected to a relatively high heat and for this reason it is necessary to line the discharge door with highly refractory material; to that end the fire-clay bricks 118 and 119 shown in perspective in Figure 25 are employed. It will be observed that these bricks each have notches, as 120, that receive a rib portion 121 on the door. This rib portion, together with an inwardly and upwardly inclined portion 122 and a plate 123 which is held in place by bolts 124, cooperates to hold the bricks 118, 119 in the door.

The structure for closing the poke-holes are clearly shown in Figures 28 and 29 and each comprises the main casting members 65 that are bolted to the track members 64 at the discharge end of the furnace; and it will be observed that the brick work which is behind the track members is recessed or cut out to receive each casting. The poke-hole cover or door, as it may be referred to, is designated as 125 and is pivotally connected at 126 to the middle of a lever 127 fulcrumed at 128 to lugs on the casting 65. The free end of this lever is held in place by a pivoted yoke 129. The poke-hole cover or door is lined by a circular fire-clay brick shown in section in Figure 29 and this fire-clay brick is held in place by a bolt, as 130.

While the furnace may have a general application it has been particularly designed for use in the carbonizing of briquets made,

for example, according to the process of either of patents previously preferred to. When the furnace has been brought to its proper heat, the poke-hole openings and the charging door being closed, the door of the lower charging chute is opened and the compartments supplied thereby are filled with briquets. This door is then closed and the door of the upper charging opening is opened and briquets are charged into the upper set of carbonizing spaces 34 and 35. This upper charging door is then closed and the carbonizing operation proceeds, the gases and vapors being carried off through the piping 44. When the carbonizing operation is completed the charge is removed through the discharge opening that is normally closed by the door 111 but in case any portion of the charge sticks in any of the carbonizing spaces it is dislodged by poke-rods inserted, as through the discharge opening or through the poke-holes 42. However, before opening the discharge door the valve 45^a is moved to its lowermost position closing the entrance to the hydraulic main and opening the passageways 45^b leading to the atmosphere or stack by means of piping 45^a. This passageway is left open until the carbonizing of the first charge has proceeded to a point where the gases leaving the retort are sufficiently rich to put into the gas holder and then the valve 45^a is raised to its uppermost position shutting off the passageways leading to the atmosphere or stack and opening the passageway to the hydraulic main from which the gases are passed to any suitable gas cleaning and collecting apparatus.

What is claimed is:

1. A carbonizing furnace comprising a carbonizing portion and a recuperator portion, said furnace having spaced vertically and transversely extending end walls, one at the charging end of the furnace and the other at the discharging end thereof, and spaced vertically and longitudinally extending main side walls all of which walls are common to said carbonizing and recuperator portions, the recuperator having a roof inclined from the end wall at the charging end and extending horizontally from side wall to side wall, which roof has a step formation on its upper surface; longitudinal intermediate walls extending from end wall to end wall and from the furnace foundation upwardly to said recuperator roof, each of which intermediate walls forms partitions between the air inlet passageways or conduits and the outgoing waste combustion gas passageways or conduits of the recuperator whereby an interchange of heat between the outgoing gases and incoming air is enabled to be effected, said intermediate walls and said recuperator roof being of fire brick, the carbonizing portion of the furnace having a

main roof extending from end wall to end wall and from side wall to side wall; a main floor portion of silica brick extending from end wall to end wall and substantially from 5 side wall to side wall, which main floor portion has an inverted step formation on its under surface and rests upon the roof of the recuperator; vertically and longitudinally extending intermediate walls arranged in 10 sets and providing between the walls of each set a carbonizing chamber or retort, which intermediate walls are of silica brick and extend from end wall to end wall and from said main floor portion to said roof 15 and serve to support in part the latter; partitions of fire-clay brick in each carbonizing compartment serving to sub-divide the carbonizing chamber into inclined carbonizing spaces, and within each carbonizing chamber 20 a fire-clay floor portion resting upon said main floor portion; a series of vertically and transversely extending partitions of silica brick arranged between adjacent walls of adjacent sets; a series of vertically 25 and transversely extending partitions extending practically from each side wall to the wall adjacent thereto of the set of intermediate walls next to the side walls, all of which said vertically and transversely extending 30 partitions serve to define in part combustion flues that are located at each side of the carbonizing spaces, the construction being such that expansion spaces gradually increasing in width in passing from 35 one end of the furnace toward the other end are left between the verticals of the step upper surface of the recuperator fire-clay brick roof and the inverted step under surface of the carbonizing portion when the 40 furnace is first erected, which expansion spaces are closed either wholly or in part when the furnace is heated.

2. A furnace retort having a series of inclined carbonizing chambers that are provided in a masonry construction supported on a masonry recuperator construction, the masonry recuperator construction being formed substantially wholly of fire brick and having an upper surface of step formation, the masonry retort construction being formed principally of silica brick and particularly as to those walls through which heat is transmitted, the under side of said silica brick construction being of inverted 50 step formation and resting upon the step formation of the recuperator, the construction being such that at one end of the furnace the verticals of the inverted step formation are close to the step formation of 55 the recuperator but so that in passing from that end of the furnace to the other a gradually increasing space exists between these verticals so as to take care of the differential expansion when the two types of masonry 60 structure are subjected to heat.

3. A carbonizing furnace having vertically and transversely extending end walls of fire-clay brick connected by vertically and longitudinally extending main side walls of fire clay brick between which walls 70 there rests a structure of silica brick that provides a floor portion and side walls of the carbonizing portions or retorts of the furnace, which silica brick structure rests upon a fire-clay brick structure that provides a recuperator for the furnace, which recuperator has an inclined roof portion and spaced intermediate vertically and longitudinally extending walls that separate the outgoing products of combustion from 80 the incoming air and that serve to support in part the recuperator roof, the upper surface of said roof being of step formation, the under portion of said silica brick construction being of inverted step formation 85 and resting upon said roof, the arrangement of the recuperator roof and of the inverted steps of said silica brick construction being such that expansion spaces are provided between the majority of the verticals of said 90 step and inverted step formations and which expansion spaces gradually increase in passing from a place where the verticals of the silica brick construction are in engagement with or in close proximity to the verticals 95 of the fire brick portion of the recuperator.

4. A carbonizing furnace having vertically and transversely extending end walls of fire-clay brick connected by vertically and longitudinally extending main side walls 100 of fire clay brick, a main roof of fire-clay brick extending from side wall to side wall and from end wall to end wall, a recuperator roof of fire-clay brick extending from side wall to side wall and from end wall 105 to end wall which recuperator roof is inclined from the charging end of the furnace, spaced intermediate vertically and longitudinally extending walls for separating the outgoing products of combustion 110 from the incoming air but permitting a transfer of heat from the outgoing products of combustion to the incoming air, which last-mentioned walls extend upwardly to and support in part said recuperator roof, the upper portion of said inclined recuperator roof being of step formation, a silica brick portion having a main floor member that rests upon the recuperator roof that extends from end wall to end wall and 115 nearly the full width of the space between the side walls, said silica brick portion having vertically and longitudinally extending intermediate walls that extend from end wall to end wall and from said main floor member to said main roof so as to support the latter in part, said silica brick portion being constructed so as to provide the vertical walls of the carbonizing chambers 120 and of the heating flues at each side of 125 130

- each carbonizing chamber, the under portion of said silica brick portion being of inverted step formation, the arrangement of the steps of the recuperator and of the inverted steps of said brick portion being such that expansion spaces are provided between a majority of the verticals of said step and inverted step formations.
5. A carbonizing furnace having vertically and transversely extending end walls and vertically and longitudinally extending side walls, an inclined floor portion between said side walls and extending from end wall to end wall, an inclined roof portion extending from side wall to side wall and from end wall to end wall, and spaced vertically and longitudinally extending intermediate walls which extend from the floor portion to the roof portion and from end wall to end wall, which furnace is characterized by having in a side wall thereof an upwardly extending air duct leading to an upwardly inclined air duct that is also within the side wall and from which inclined air duct there extends laterals or transversely extending branches that are located in the roof portion and that lead to the upper ends of vertically extending combustion flues provided at each side of carbonizing chambers that are located between adjacent intermediate walls, and by having damper controlled passageways extending from said laterals or transversely extending branches to the upper end of the combustion chambers.
6. A carbonizing furnace having a masonry construction which provides alternate carbonizing chambers and combustion flues all of which are located between vertically and longitudinally extending main side walls and which furnace is characterized by having air supplied to the combustion flues through a main duct from which lateral branches extend transversely of and above the carbonizing compartments to the upper ends of the combustion flues and by having the lower ends of the combustion flues in communication through damper controlled passageways with flues, each of which flues is located directly under and extends along a carbonizing chamber.
7. A carbonizing furnace having spaced main side walls, spaced main end walls, an inclined floor, an inclined roof, vertically and longitudinally extending intermediate walls arranged in sets and providing between the walls of each set carbonizing compartments, said intermediate walls extending from the floor to the roof and from end wall to end wall, vertically and transversely extending partitions arranged in sets so as to subdivide the space between adjacent walls of adjacent sets of intermediate walls into combustion or heating flues and so as to subdivide the space between each side wall and adjacent wall of the adjacent set of intermediate walls into combustion or heating flues, means for supplying gas at the upper ends of each combustion or heating flue, said furnace being characterized by having in each main wall thereof an inclined main air passageway from which there extends a series of laterals or transversely extending branches whereby air is supplied by each branch from the main air duct to the upper end of transversely arranged combustion or heating flues, there being a damper controlled passageway leading from each lateral or transversely extending branch to each combustion or heating flue, a damper construction at the lower end of each combustion flue, an inclined waste gas flue located immediately below and extending along each carbonizing chamber, into which waste gas flues the products of combustion pass from the vertically extending flues through damper controlled passageways, the furnace also being characterized by having a header opening or passageway for receiving products of combustion from two or more of these waste gas flues.
8. A carbonizing furnace having a masonry construction which provides a plurality of carbonizing chambers at each side of each of which there are located vertically extending flues that receive air for supporting combustion from transversely extending air ducts, that are located above and in the roof of the combustion chambers, through damper controlled passageways leading from said ducts to the combustion flues, and which masonry construction also provides a waste gas duct located below each carbonizing chamber, there being at the lower end of each combustion flue an upper damper and a lower damper which said upper damper is for regulating as desired the flow of the products of combustion from the flue and which lower or second damper is for determining the relatively permanent opening of the passageway leading from the lower end of the combustion flue to the particular waste gas flue into which the combustion flue discharges the products of combustion.
9. A carbonizing furnace having between adjacent carbonizing chambers a combustion flue common to both chambers and which combustion flue receives fuel and air for supporting combustion at its upper end and is provided with means for permitting a poker-rod to be thrust downwardly into the flue in order to adjust dampers that are at the lower end of the flue, the upper of which dampers are relied upon to regulate the temporary control of the flow of the products of combustion from the flues and the lower of which dampers is employed to determine or effect a relatively fixed opening leading from the flue to a waste gas passageway below one of the carbonizing compartments.

10. A carbonizing furnace having a masonry structure, in the lower part of the furnace structure a recuperator substantially of fire-clay brick and in the upper part a carbonizing portion the main floor portion and heat transmitting walls of which are of silica brick and constitute a silica brick structure, which furnace is characterized by spaces being left to take care of the differential expansions between the more expansible silica brick structure and the fire brick structure upon which the silica brick structure is supported. 70
11. A carbonizing furnace having a masonry structure providing a recuperator of fire-clay brick in the lower portion and a carbonizing portion that includes a silica brick structure in the upper portion, which furnace is characterized by there being spaces left to take care of the differential expansions in a longitudinal direction between the fire-clay brick structure and the more expansible silica brick structure which is supported by the fire-clay brick structure, 80
- 20 and further characterized by there being vertically extending girders at each end of the furnace, which girders are arranged in sets, there being a set at each end and also tie rods extending between the set at one end and the set at the other end, and between the girders of each set a transversely and vertically extending frame work held in place by springs which constantly press each frame work in a longitudinal direction 90
- 30 toward the masonry structure, said frame work also having vertically extending tracks against which there press rollers engaged by track members carried on the masonry structure, which rollers serve to permit a vertical 100 expansion of the masonry structure relative to the frame work. 105
12. A carbonizing furnace having a masonry structure which has a substantial vertical and also a substantial longitudinal 45 or endwise expansion characterized by having at each end of the furnace relatively fixed spaced girders or uprights and between the spaced girders or uprights at each end of the furnace a floating vertically and 50 transversely extending frame work that is normally forced in a longitudinal direction toward the brick work by spring constructions located between the vertically extending girders on the one hand and the floating vertically and transversely extending frame work on the other, vertically extending tracks carried by masonry of the furnace at each end of the furnace, corresponding vertical tracks carried by the vertically 55 and transversely extending frame work which is at each end of the furnace, and antifriction rollers between the tracks carried by the masonry construction and the tracks carried by said frame work. 115
- 60
13. A carbonizing furnace having an inclined carbonizing chamber with inclined partitions or floors therein sub-dividing the carbonizing chamber into carbonizing compartments or spaces arranged one above the other, one of said partitions being a central partition that extends to the end wall at the charging end of the furnace, the remainder of said partitions terminating short of said end wall, said furnace having charging openings, one arranged whereby material is charged into the compartments above said central partition and another arranged whereby material is charged into the compartments below said central partition, the lower end of each partition terminating short of the end wall at the discharging end of the furnace whereby all of the contents of the furnace can be discharged through a single opening which is located at the lowermost portion of the carbonizing compartment, said furnace having suitable doors for closing the charging opening and the discharging opening, said furnace also being provided with poke openings whereby each compartment above the lowermost compartment is accessible by a poke-rod inserted through the poke opening corresponding to the compartment and also with plugs for normally closing said poke openings. 120
14. A carbonizing furnace having vertically and transversely extending end walls of fire-clay brick, vertically and transversely extending main side walls of fire-clay brick, suitable tie-rod constructions for holding the end walls and side walls in place, a masonry construction formed of fire-clay brick and providing a recuperator in the lower portion of the furnace, which recuperator extends from end wall to end wall and from side wall to side wall, a masonry construction of silica brick extending from end wall to end wall but terminating slightly short of the side walls so as to provide an expansion space between the side walls and the silica brick construction, which silica brick construction rests upon the fire brick construction of the recuperator and is provided with expansion spaces to take care of the greater expansion in a longitudinal direction of the silica brick resting upon the fire brick, the silica brick construction being made so that it provides a plurality of inclined carbonizing compartments with vertically extending heating flues on each side of each compartment, the masonry structure as a whole having transversely extending header openings or passageways part of which receive the hot gases from the recuperator and conduct them to main air passageways that lead upwardly 125 to the roof portion of the furnace, the other of which header openings or passageways receive the products of combustion conducted to it by inclined waste gas flues leading from the combustion flues, which last 130

mentioned header openings or passageways serve as means whereby said products of combustion are conveyed to the recuperator, said furnace also having in the roof portion thereof laterals or transversely extending branches leading from said main air passageways to the upper end of the combustion flues, each of said inclined waste gas flues being located below a carbonizing chamber.

This specification signed the 20 day of ¹⁰ Mch. A. D. 1920.

CHARLES HOWARD SMITH.
